BEVERAGE COOLER AND DISPENSER

John S. Mittelstaedt and August J. Rantz, New Orleans, La.

Application December 13, 1939, Serial No. 309,070

1 Claim. (Cl. 62—147)

The invention relates to a cooler and more especially to a beverage cooler and dispenser.

The primary object of the invention is the provision of a device of this character wherein the same involves what may be termed a cartridge which can be readily separated from a dispensing fixture and when attached will be located in a refrigerant or ice chamber or a refrigerator compartment so that its contents can be cooled prior to the dispensing of the same, the device being more sanitary than cooling coils and assures a cooling with dispatch.

Another object of the invention is the provision of a device of this character wherein on separation thereof from a dispensing fixture it can be easily and thoroughly cleaned, being of a construction to prevent a beverage from flowing too freely and results in a better drink properly cooled.

A further object of the invention is the provision of a device of this character wherein the same can be relieved of congested air to assure the filling thereof with beverage and the proper flow of the same when dispensed and is of a construction to enable the same to be conveniently placed within a refrigerating compartment or the like.

A still further object of the invention is the provision of a device of this character, which is simple in its construction, thoroughly reliable and efficient in operation, assuring the cooling of liquid for drinking consumption, thoroughly sanitary, and inexpensive to manufacture and install in a flow conduit for dispensing the liquid.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a side elevation partly in section of the device constructed in accordance with the invention.

Figure 2 is an enlarged fragmentary vertical sectional view through the upper portion of the device.

Figure 3 is a view similar to Figure 2 through the lower portion of the device.

Figure 4 is a fragmentary vertical sectional view through a cooling or refrigerating box showing the device arranged in association therewith.

Similar reference characters indicate corre-

sponding parts throughout the several views in the drawing.

Referring to the drawing in detail, A designates generally the device constructed in accordance with the invention and may be termed a beverage cartridge involving an elongated cylindrical body 10 having reversely tapered upper and lower ends 11 and 12, respectively, and adapted to be accommodated within the cartridge for liquid to be cooled and dispensed in a manner presently described.

The upper tapered end 11 is formed with a nipple both externally and internally threaded, the nipple being denoted at 13 for separable connection with a coupling union 14 of a dispensing faucet 15, which is valved to regulate and cut off flow thereto, the valve being generally indicated at 16, and is hand operated.

On the lower tapered end 12 is swiveled a coupling 17 for connection with an inlet pipe 18 which supplies liquid to the interior of the cartridge A. This liquid introduced is conveyed upwardly within the body 10 by a pipe 19, which rises within the body 10 to an uppermost point thereof and is formed with a laterally-turned tip 20 for delivering the supply of liquid into the body 10 at a high or elevated point therein. This pipe 19 has fluid-tight connection with the body 10 at the lower tapered end 12 next to the coupling 17.

Fitting the nipple 13 is a depending pipe 21, which extends downwardly within the body 10 into a lower point therein and is formed with a laterally-bent tip 22. The pipe 21 communicates with the faucet 15 and delivers liquid contained within the body 10 thereto for the dispensing of said liquid thereby.

Below the internal threads of the nipple 13 is an annular flange 13'. The upper end of the pipe 21 is provided with a laterally turned flange 14' resting upon the flange 13'. Screwed within the internal threads of the nipple 13 is a tap 15', which clamps the laterally turned flange 14' of the pipe 21 on the flange 13'. The tap 15' is provided with a central opening 16' communicating with the pipe 21.

In the use of the cartridge A when within a dispensing conduit for liquid, for example, beverages to be drunk, the body 10 is placed within a refrigerant, in this instance, cracked ice 23 contained within a receptacle, as, for example, a box, a portion thereof being indicated at 24. The lower tapered end 12 of the said body is fluid-sealed with the box 24 at its bottom so that the cartridge A assumes an upright vertical posi-

tion to be surrounded by the cracked ice 23 for the cooling of the contents of the body 10 prior to the dispensing of such contents through the faucet 15.

At the upper tapered end 11 and built therewith is a hand valve 25 controlling an air vent 26 leading to the atmosphere from the interior of the body 10 and this vent is opened by the valve 25 only when the cartridge A is being filled with liquid so as to let out therefrom to the atmosphere congested air within said cartridge. The liquid is admitted to the cartridge A through the tip 20 and discharged therefrom through the tip 22 of the respective nozzles 19 and 21 and such liquid on the cooling thereof is dispensed through the faucet 15.

The body 10 by reason of its separation from the faucet 15 and the pipe 18 allows of the easy cleaning of the body 10 to render the same sanitary, there being no waste of liquid when the cartridge A is associated with the faucet 15 and the inlet pipe 18 for said liquid.

It is of course understood that this cartridge when in association with dispensing equipment can be placed within a refrigerator or within a receptacle containing refrigerant so that the content of the cartridge A will be chilled or cooled

prior to the dispensing thereof, the said cartridge being adaptable for the service of chilled drinking water or beverages.

What is claimed is:

- 5 A device of the kind described, comprising an elongated cylindrical body having reversely tapered upper and lower ends, a substantially cup shaped nipple having internal and external threads, a flange within the nipple below the internal threads, a delivery pipe depending within said body and having an annular flange at its upper end for reception within said nipple and seated upon the flange, a central perforated retaining member screwed within the threads of the nipple and engaging the flange on the pipe and tightly seating the same on the flange in the nipple, a dispensing faucet detachably coupled with said nipple, a turn coupling engaging the external threads of said nipple for fastening the dispensing faucet thereto, a supply pipe within the lower end of the body and having a separate connection therewith, said pipe being reversely directed and terminating laterally adjacent to the wall of said body, and a venting device at the upper end of said body.
